FIG. 1 is a perspective view of a capnography fitting;
 FIG. 2 is a side view of the capnography fitting;

FIG. 3 is a side view of the capnography fitting;

FIG. 4 is a back view of the capnography fitting;

FIG. 5 is a front view of the capnography fitting;

FIG. 6 is a top view of the capnography fitting; and,

FIG. 7 is a bottom view of the capnography fitting.

The broken lines in the figures show portions of the capnography fitting that form no part of the claimed design.
